UNITED STATES PATENT OFFICE.

ROBERT M. BYERS, OF BROOKLYN, NEW YORK.

GARTER.

1,424,801.

Specification of Letters Patent. Patented Aug. 8, 1922.

Application filed June 2, 1919. Serial No. 301,260.

To all whom it may concern:

Be it known that I, ROBERT M. BYERS, a citizen of the United States, residing at Brooklyn, in the county of Kings and State 5 of New York, have invented new and useful Improvements in Garters, of which the following is a specification.

This invention relates to a garter which is essentially adapted for securing a stocking 10 by means of a clasp connected to an elastic leg encircling band.

An object of the invention is to provide the band with non-corrodible members preferably consisting of celluloid so that moisture 15 cannot deteriorate or rust the members and thus soil the garments.

Another object of the invention is to provide the clasp with longitudinal slots, one being behind the other, and a stud or button 20 slidingly mounted in the slots to engage the stocking.

Another object of the invention is to shape the clasp from a single sheet of material and to provide it with a lateral lug for 25 adjustably attaching one end of the elastic band.

The invention is also designed to include means for removing the elastic band from the clasp when it becomes worn or useless 30 and substituting another merely by attaching one end of the band to the lateral lug and mounting a slotted hook engaging member to its other end.

The novel features of the invention are 35 more fully described in the following specification and claims and illustrated in the accompanying drawing in which:—

Figure 1 represents a front elevation of a garter embodying this invention.

Figure 2 is a similar view of the clasp.

Figure 3 is a vertical longitudinal section of the same.

Figure 4 is a view of the blank.

Figure 5 is a perspective view of a slotted 45 hook engaging member.

Figure 6 is a sectional side elevation of the same, showing the end of the band clamped between the jaws.

Figure 7 is a horizontal section taken 50 along the line 7—7 of Fig. 1.

In the drawing the numeral 9 designates a band which is formed of elastic webbing and adapted to encircle the leg of a person when the garter is in use. A clasp consisting of a rear member or frame 10 provided 55 with a longitudinal key slot 11 and having

a front tongue member 12 with a key slot 13 is attached to one end of the band. The means for attaching the band to the clasp includes a lateral lug 14 projecting at an 60 angle from the back and having a pair of slots 15 with an intermediate slot 16 provided with a serrated edge 17 to engage the band. The band is passed through the slots and looped about the bars formed between 65 the slots with the end extending between the tongue and the back of the clasp as indicated in Figures 1 and 7. The serrations bite into the body of the band, while the end portion is held taut or clamped and hidden 70 between the two members. The band can be lengthened or shortened circumferentially while it is about the leg merely by moving the end from between the two members and disengaging the body of the band from the 75 serrations thus permitting it to be drawn through the slots.

Opposite to the lug on the back member is located a hook 18 for engagement with a slotted member 19 best seen in Figure 1. 80 The lug and the hook are each set at an obtuse angle to the body of the clasp so as to give the elastic a snug fit about the leg and wrinkling is eliminated. The slotted member is secured to the end of the band by 85 clamping the band between serrated jaws 20. The slotted member is formed of a sheet of celluloid doubled while hot and the teeth are cut in the turned edges of the jaws after it is shaped as shown. When it is desired 90 to renew the band the slotted member can be removed by springing the jaws apart and the member used to mount another band.

The device for securing a stocking to the clasp comprehends a button or stud having 95 a head 21 with a stem 22 and a back 23 formed of celluloid. A portion of the stem is of larger diameter forming a shoulder and between it and the inner surface of the head is clamped a disk of rubber 24 to engage the fabric.

It will be seen that when the button is in place it can be slid up or down within the limits of the slots. The rear slot is longer than the slot in the tongue so that the button 105 when in register with the key hole in the rear slot can be removed or inserted. The clasp has sufficient resiliency to move the tongue away from the back when the button is moved up out of register with the key 110 hole in the tongue slot. When the head of the button is in line with the key hole

2
or enlarged part of the slot in the tongue it permits the fabric to be passed between the tongue and back and about the head of the button. In order to fasten the fabric 5 the tongue is pressed toward the back bringing the head of the button with the fabric outside of the key hole, and the button can then be slid downward as shown in Fig. 3, to clamp the portions of the fabric adjacent 10 to the head between the tongue and its slot.

As indicated in Figure 4 the blank for forming the clasp is preferably composed of a sheet of flat celluloid which can be moulded into the shape shown in Figure 1 by doubling 15 it longitudinally while it is hot or in a semi-plastic state. The slots are cut in the body of the sheet before it is doubled and the teeth in the edge of the slot in the lug are filed or cut as shown after the sheet cools.

20 I claim:—

1. A garter comprising a clasp having back and front members, keyhole slots formed in the members, a button slidingly arranged in the slots, a lateral slotted lug 25 projecting at an angle from the back to adjustably attach one end of an elastic band, and a hook located opposite to the lug for engagement with another end of the band.

2. A garter comprising a clasp having 30 back and front members, keyhole slots formed in the members, one being longer than the other, a button slidingly arranged in the slots, a lateral slotted lug projecting at an angle from the back to adjustably at-

60 tach one end of an elastic band, a hook located at an angle opposite to the lug, and a slotted member detachably connected to the other end of the band for engagement with the hook.

3. A garter comprising a clasp having 40 back and front members, key hole slots formed in the members, one being behind the other, a button slidingly arranged in the slots, a lateral slotted lug projecting at an angle from the back to adjustably attach one end of an elastic band, a hook located at an angle opposite to the lug, and a slotted member secured to the other end of the band for engagement with the hook.

4. A celluloid blank adapted to form a 45 50 clasp for garters having a pair of longitudinal slots, one being above the other, and a lateral lug extending at an angle from the body of the blank.

5. A celluloid blank adapted to form a 55 60 clasp for garters having a pair of longitudinal key hole slots, one being above the other, a lateral slotted lug extending at an angle from the body of the blank, and a lateral projection opposite to the lug.

In testimony whereof I have hereunto set my hand in the presence of two subscribing witnesses.

ROBERT M. BYERS.
